(57) CLAIM

The ornamental design for a spatula, as shown.

DESCRIPTION

FIG. 1 is a top plan view of the spatula, showing, in particular the ornamental design thereof;

FIG. 2 is a back elevational view thereof;

FIG. 3 is a front elevational view thereof;

FIG. 4 is a perspective view thereof; and,

FIG. 5 is a side elevational view thereof.

It will be understood that the applicant disclaims the handle as shown in phantom in the drawings.
